GEORGE L. PARKER, OF BREMERTON, WASHINGTON, ASSIGNOR OF ONE-HALF TO CHARLES H. GAFFNER, OF SEATTLE, WASHINGTON.

WEATHER-STRIP.

SPECIFICATION forming part of Letters Patent No. 752,355, dated February 16, 1904.

Application filed September 30, 1903. Serial No. 175,147. (No model.)

To all whom it may concern:

Be it known that I, GEORGE L. PARKER, a citizen of the United States, residing at Bremerton, in the county of Kitsap and State of Washington, have invented certain new and useful Improvements in Weather-Strips, of which the following is a specification, reference being had therein to the accompanying drawings.

10 This invention relates to weather-strips, and particularly to the application of such devices upon doors.

The object of the invention is to provide an efficient device of this character of simple and inexpensive construction, which will be raised clear of the floor when the door to which it is applied is opened and pressed down upon the door-sill into operative position coincident with the closing of the door.

20 To these ends the invention consists in the novel construction and combination of parts, as will be hereinafter described, and pointed out in the claim.

In the accompanying drawings, showing the preferred form of my invention, and wherein similar letters designate corresponding parts in the several views, Figure 1 is a front elevation of a weather-strip embodying my invention, which is shown secured in place upon 30 a door with the front of the containing-case thereof removed. Fig. 2 is a perspective view of the same. Figs. 3 and 4 are enlarged vertical sections taken on line $\alpha\alpha$ of Fig. 1 and showing, respectively, the parts in operative 35 and inoperative positions.

The letter a designates a base-plate adapted to be fixedly secured, as by screws b , to the bottom rail D of a door and having at its extremities rectangular bends c c' , which provide ends for a containing-case, to which the front or shield portion d thereof is secured by screws engaging in apertures e , and which is likewise fastened directly to the door by screws, such as f .

45 g is a plate slidably secured against the said

base-plate by screws h , passed through vertically-arranged slots h' therein, and having along its lower edge a resilient gasket i , made, preferably, of rubber tubing.

k is a rod supported in a plurality of brackets l , integral with the base-plate and which may advantageously be punched therefrom, so as to project outwardly, as shown in the drawings. Arms m and n are rigidly attached to the said rod, the former being arranged to be 55 in the same plane, and are pivotally connected adjacent their outer ends by hangers o to the said movable plate, whereby it is raised or lowered when the rod is given a partial rotation, as will presently be described. The arm n , 60 which is upon the extremity of the rod and outside of end c of the case, is positioned so as to be impinged by the jamb of the door-casing when the door is shut thereagainst and cause the said rod to rotate and force the 65 resilient gasket carried by the sliding member into operative or compressed contact with the door-sill. A spiral spring p is provided to surround the said rod and is connected, respectively, at its opposite ends to the rod and 70 to the casing thereof and arranged to normally retain the gasket in its raised or disengaged position, which it will obviously do as soon as the door has been opened sufficiently to move the actuating-arm n out of its 75 engagement with the door-jamb.

The operation of the invention is evident from the foregoing specification and needs no further description here. It may be mentioned, however, that the device accomplishes 80 the purposes for which intended in a simple and positive manner and, having few parts, does not easily get out of order, and is entirely automatic in its action. It will close the opening beneath the door to which it is applied, so 85 that air and water can find no passage therethrough. It does not wipe along the floor as the door is swung and is operative as a weather-strip only while the door is closed.

Having described my invention, what I 90

claim as new, and desire to secure by Letters Patent, is—

In a device of the character described, in combination, a containing-case, a rod extending lengthwise of the casing and rotatably mounted in supports integral of the casing, arms fixedly secured to the said rod and connected by hangers with a movable plate, said movable plate provided along its lower edge with an elastic gasket, a spring adapted to

raise the said plate, and another arm integrally secured to the end of the said rod and exteriorly of the case.

In testimony whereof I affix my signature in presence of two witnesses.

GEORGE L. PARKER.
